SWITCHBOARD

Ervin E. Wills, Affton, Mo., assignor to Westinghouse Electric Corporation, East Pittsburgh, Pa., a corporation of Pennsylvania.

Application May 2, 1947, Serial No. 745,409.

12 Claims. (Cl. 175—298)

1

My invention relates, generally, to switchboards and, more particularly, to switchboards for supporting control apparatus of the type utilized for controlling distribution circuits. The control of such circuits requires various forms and sizes of motor starters, circuit breakers, disconnect switches, etc.

Furthermore, since the electric power utilizing devices in industrial plants are frequently changed, the control apparatus for such devices must also be changed and rearranged. In the past, numerous attempts have been made to standardize the switchboard control panels for such apparatus.

An object of my invention is to provide a standardized switchboard panel unit which may be installed individually or in groups containing any number of units.

Another object of my invention is to provide for the easy interchange of control apparatus units of different ratings within the same switchboard assembly.

A further object of my invention is to increase the safety of a switchboard structure.

A more general object of my invention is to provide a switchboard structure which shall be simple and efficient in operation and which may be economically manufactured and installed.

Other objects of my invention will be explained fully hereinafter, or will be apparent to those skilled in the art.

In accordance with one embodiment of my invention, the side plates of a switchboard panel unit are constructed to form a vertical duct for the bus bars to which control apparatus units are connected. The apparatus units are provided with contact members of a floating type to facilitate the insertion and the removal of the units. Mechanical interlocking is provided to prevent the removal of a unit while it is conducting current.

For a better understanding of the nature and objects of my invention, reference may be had to the following detailed description, taken in conjunction with the accompanying drawings, in which:

Figure 1 is a view, in perspective, of a switchboard structure embodying the principal features of my invention;

Fig. 2 is a view, in front elevation, of one of the switchboard panel units shown in Fig. 1, the apparatus units being removed from the structure;

Fig. 3 is a view, partially in side elevation and partially in section, of a typical panel unit;

2

Fig. 4 is a view, partially in plan and partially in section, of the panel unit shown in Fig. 2;

Fig. 5 is a view, in perspective, of a portion of a panel structure, the apparatus units being omitted;

Fig. 6 is an enlarged view, in perspective, of one of the plug-in contact units utilized in the switchboard structure, and

Fig. 7 is an enlarged view, in perspective, of another plug-in contact unit utilized in the switchboard structure.

Referring to the drawings, and particularly to Fig. 1, the switchboard structure shown therein comprises two panel sections 10 which are disposed in side-by-side relation. The panel sections 10 are of uniform height and depth and are preferably of the same width. In order to simplify the drawings, only two panel sections have been shown; however, it will be understood that as many sections as desired may be provided.

As shown, a plurality of apparatus units 11 are removably mounted on the panel sections. The particular apparatus units shown in the present drawing are motor starter units, each unit comprising a circuit breaker and motor starting devices of a type suitable for controlling the operation of electric motors of various ratings. The apparatus units 11 are designed in multiples of a fixed dimension to permit the simple and easy interchanging of units suitable for controlling motors of different ratings. It is to be understood, however, that the present switchboard structure may be utilized for supporting electrical apparatus units of other types.

As shown most clearly in Fig. 5, each panel section 10 comprises four side plates 12 having integral portions bent to provide a wiring channel 13 for each side plate and so spaced as to provide a bus duct 14 between the side plates.

An inturned flange 15 is provided on the front edge of each side plate 12 and, as shown in Fig. 1, openings 16 are provided in the flanges 15 for attaching the apparatus units 11 to the side plates 12. The wiring channel 13 for each side plate is partially enclosed by an inner wall 17 formed integrally with the side plate 12, an integral flange 18 and a mounting strip 19, which may be secured to the side plate 12 in any suitable manner such as by spot welding.

As shown, two side plates 12 may be bolted or welded together to form the side members of each panel section. The two side members are spaced apart to provide the bus duct 14 between the inner walls 17 of the side members.

Bus bars 21 may be disposed vertically in the

bus duct 14. The bus bars 21 may be supported by insulating members 22 which, as shown most clearly in Fig. 4, may be attached to the inner walls 17 of two of the side plates 12 by bolts 23. Insulating barriers 24 may be attached to the flanges 18 of the side plates 12 by screws or bolts 25 on opposite sides of the bus bars 21, thereby substantially enclosing the bus duct 14.

As shown most clearly in Figs. 1, 2 and 3, main bus bars 26 may be disposed horizontally at the top of the switchboard structure. The main bus bars 26 extend through openings 27 provided in the side plates 12 and incoming power cables 28 may be secured to the main bus bars 26 in any one of the panel sections. The vertical bus bars 21 in each panel section may be bolted to the main bus bars 26, as shown in Fig. 3.

The outgoing power connections from the apparatus units in each panel section may be made to terminal blocks 29 which are mounted on a horizontal mounting strip 31 located near the top of the panel structure. The control wiring connections may be made to additional terminal blocks 32 also mounted near the top of the panel structure. Additional openings 33 may be provided in the side plates 12 to permit cross panel wiring between the panel sections.

As shown most clearly in Fig. 1, each apparatus unit 11 comprises a semi-enclosed cabinet having a rear wall 34, partial side walls 35 and a hinged door 36. The cabinet is supported in the panel structure by channel shaped members 37, secured to the sides of the cabinet, and which slide on brackets 38 which are secured to the side plates 12. The cabinet may be retained in position by screws 39 which are inserted in the openings 16 in the flanges 15 of the side plates 12.

It will be seen that the screws 39 for each cabinet are covered by the door 36 for that cabinet when the door is closed. A suitable interlocking mechanism 41, which is actuated by a handle 42 on the door 36, is provided to prevent the door 36 from being opened while the circuit breaker in that apparatus unit is closed. Thus, the door 36 for any unit cannot be opened to gain access to the screws 39 while the apparatus in that unit is energized. Therefore, the cabinet cannot normally be removed while the apparatus is conducting current.

A device 43, which may be actuated by a screw 44 extending through the door 36, is provided for releasing the interlocking mechanism 41 by an authorized person without operating the handle 42 to open the circuit breaker. Therefore, an additional electrical interlock 45 is provided for each cabinet to prevent the cabinet from being withdrawn while the apparatus in the cabinet is conducting current. The interlock 45 comprises a suitable switch which is actuated by a member 46 secured to the flange 18 of a side plate 12 and functions to cause the deenergization of the apparatus in a particular cabinet when that cabinet is being withdrawn from the switchboard structure. The interlock 45 functions to deenergize the apparatus before the cabinet can be withdrawn sufficiently to interrupt the power connections between the bus bars 21 and the apparatus in the cabinet.

In order to facilitate the installation of the apparatus units in the switchboard structure, plug-in contact members are provided for establishing both the main power and the control connections to the individual units. As shown, fixed contact members or studs 47 are secured to the bus bars 21. Floating contact members 48 are mounted

in the rear wall 34 of each cabinet for engaging the fixed contact members 47 when the cabinet is installed in the switchboard structure.

As shown most clearly in Fig. 7, each set of floating contact members 48 comprises a plurality of individual contact members 49 of a type suitable for engaging the studs 47. The individual contact members 49 are disposed between two strips 51 of insulating material which are attached to the rear wall 34 of the cabinet. Each individual contact member has a circular portion 52 which is disposed in oppositely positioned semi-circular notches in the insulating strips 51. The diameter of the semi-circular notches may be made slightly larger than the diameter of the circular portions 52 of the contact members, thereby permitting a predetermined amount of movement of each contact member relative to the supporting strips 51. In this manner, accurate alignment of the floating contact members 48 with the fixed contact studs 47 is not required. Terminal studs 53 are provided on the individual contact members 49 for making the connections to the electrical apparatus in the cabinet.

As shown in Fig. 6, floating contact members 54 and 55 are provided for making the outgoing power connections to the apparatus units and also for making the control connections. Each contact member 54 comprises a plurality of contact studs 56, see Fig. 1, which are secured in an insulating block 57. The block 57 is movably mounted between insulating members 58 which may be secured to mounting strips 59 attached to the flange 18 and the vertical mounting strip 19 on the side plate 12. As shown in Fig. 6, a slot 61 may be cut in each end of the insulating block 57, and a rectangular notch 62 may be provided in one end of each insulating member 58. A rectangular projection 63, which extends into the notch 62, may be provided in the slot 61 on each end of the insulating block 57. By making the projections 63 slightly smaller than the notches 62, the insulating block 57 is permitted to move a predetermined amount relative to the supporting members 58.

The cooperating contact members 55 which engage the contact studs 56 are mounted in a manner similar to the members 54. As shown, the individual contact members are mounted in an insulating block 64 which is similar to the block 57 except being of a greater depth to accommodate the individual contact members. The blocks 64 are mounted between the insulating members 58 in the manner hereinbefore described. Thus, the apparatus units may be readily installed in the switchboard without requiring accurate alignment of the cooperating contact members.

It will be seen that each set of vertical bus bars 21 supplies power to apparatus units mounted on the front and the rear of each panel section, thereby reducing the amount of copper required for making the electrical connections to a relatively large number of apparatus units. Furthermore, the bus bars are substantially enclosed, thereby preventing contact with the bus bars when the apparatus units are being removed or installed.

As previously explained, the apparatus units are constructed in multiples of a fixed dimension, thereby permitting the units to be readily interchanged. Thus, two of the smaller units will fit into the space of one of the larger units shown in the present drawing. It will be understood

that still smaller or larger units than those illustrated may be utilized if desired.

From the foregoing description, it is apparent that I have provided a standardized vertical panel section on which may be mounted apparatus units suitable for controlling the operation of motors of various ratings. The present structure is provided with substantially enclosed power conductors for safety and provision is made for readily removing or installing the individual apparatus units. The apparatus units may be mounted either on the front of the switchboard structure or back-to-back as shown without changing the basic section assembly. The present structure permits the installation of a relatively large number of individual apparatus units in a relatively small amount of space.

Furthermore, access may be had to any one of the individual units without disturbing the connections to the individual unit or other units in the structure. Also, access may be had to the wiring connections between any unit in the structure and the terminal connections at the top of the panel without disturbing adjacent units or the connections thereto. The wiring channels and the bus duct provide complete isolation of the power buses outgoing power cables and control wiring connections in the vertical sections.

Since numerous changes may be made in the above-described construction and different embodiments of the invention may be made without departing from the spirit and scope thereof, it is intended that all matter contained in the foregoing description or shown in the accompanying drawings shall be interpreted as illustrative and not in a limiting sense.

I claim as my invention:

1. In a switchboard structure, in combination, four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members, and apparatus units removably disposed between the outermost portions of said side plates on opposite sides of said bus bars and electrically connected to said bus bars.

2. In a switchboard structure, in combination, four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members, apparatus units removably disposed between the outermost portions of said side plates and supported thereby, said apparatus units being disposed on opposite sides of said bus bars, and means for electrically connecting the apparatus units on opposite sides of the bus bars to the same bus bars.

3. In a switchboard structure, in combination, four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members,

apparatus units removably disposed between the outermost portions of said side plates and supported thereby, said apparatus units being disposed on opposite sides of said bus bars, and means movably mounted on said apparatus units for electrically connecting the apparatus units on opposite sides of the bus bars to the same bus bars.

4. In a switchboard structure, in combination, 10 four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members, contact members secured to opposite sides of said bus bars, apparatus units removably disposed between the outermost portions of said side plates on opposite sides of said bus bars, and contact members movably mounted on said apparatus units for engaging the contact members on the bus bars.

5. In a switchboard structure, in combination, 15 four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members, contact members secured to opposite sides of said bus bars, apparatus units removably disposed between the outermost portions of said side plates and supported thereby, said apparatus units being disposed on opposite sides of said bus bars, and contact members movably mounted on said apparatus units for engaging the contact members on the bus bars.

6. In a switchboard structure, in combination, 20 four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members, contact members secured to opposite sides of said bus bars, apparatus units removably disposed between the outermost portions of said side plates and supported thereby, said apparatus units being disposed on opposite sides of said bus bars, and contact members movably mounted on said apparatus units for engaging the contact members on the bus bars.

7. In a switchboard structure, in combination, 25 four side plates having integral portions bent inwardly and disposed to form a bus duct between the innermost portions of the plates, in-turned portions of two of said plates at each side of the structure being disposed back-to-back and joined together to form a side member of the switchboard structure, bus bars vertically disposed in said duct between said side members, contact members secured to opposite sides of said bus bars, apparatus units removably disposed between the outermost portions of said side plates and supported thereby, said apparatus units being disposed on opposite sides of said bus bars, and contact members movably mounted on said apparatus units for engaging the contact members on the bus bars.

additional contact members movably mounted on the apparatus units for engaging the first-named contact members when the apparatus units are connected to the bus bars.

8. In a switchboard structure, in combination, spaced side plates having integral portions bent inwardly and disposed to form a bus duct between the innermost portions of the plates, inturned portions of said plates at each side of the structure being disposed back-to-back and joined together to form a side member of the switchboard structure, bus bars vertically disposed in said duct between said side members, apparatus units removably disposed between the outermost portions of said side plates on opposite sides of the bus bars and electrically connected to the same bus bars, brackets secured to said side plates, and supporting members on said units for slidably engaging said brackets to support said units.

9. In a switchboard structure, in combination, spaced side plates having integral portions bent inwardly and disposed to form a bus duct between the innermost portions of the plates, inturned portions of said plates at each side of the structure being disposed back-to-back and joined together to form a side member of the switchboard structure, bus bars vertically disposed in said duct between said side members, apparatus units removably disposed between the outermost portions of said side plates on opposite sides of the bus bars and electrically connected to the same bus bars, brackets secured to the inside surfaces of said side plates, and channel-shaped members on said units for slidably engaging said brackets to support said units.

10. In a switchboard structure, in combination, spaced side plates having integral portions bent inwardly and disposed to form a bus duct between the innermost portions of the plates, inturned portions of said plates at each side of the structure being disposed back-to-back and joined together to form a side member of the switchboard structure, bus bars vertically disposed in said duct between said side members, apparatus units removably disposed between the outermost portions of said side plates on opposite sides of the bus bars and electrically connected to the same bus bars, horizontally disposed brackets secured to the inside surfaces of said side plates, and horizontally disposed members on said units for slidably engaging said brackets to support said units.

11. In a switchboard structure, in combination, spaced side plates having integral portions bent inwardly and disposed to form a bus duct between the innermost portions of the plates, inturned portions of said plates at each side of the structure being disposed back-to-back and joined together to form a side member of the

switchboard structure, bus bars vertically disposed in said duct between said side members, a plurality of apparatus units removably disposed between the outermost portions of said side plates on opposite sides of the bus bars, each unit comprising a cabinet having a rear wall, flanged side walls and a door hinged to one of the side walls, horizontally disposed brackets secured to the inside surfaces of said side plates, horizontally disposed members secured to the side walls of said cabinets for slidably engaging said brackets to support said units, and contact means supported by the rear walls of said cabinets for electrically connecting the apparatus units to the same bus bars.

12. In a switchboard structure, in combination, spaced side plates having integral portions bent inwardly and disposed to form a bus duct between the innermost portions of the plates, inturned portions of said plates at each side of the structure being disposed back-to-back and joined together to form a side member of the switchboard structure, bus bars vertically disposed in said duct between said side members, a plurality of apparatus units removably disposed between the outermost portions of said side plates on opposite sides of the bus bars, each unit comprising a cabinet having a rear wall, flanged side walls and a door hinged to one of the side walls, horizontally disposed brackets secured to the inside surfaces of said side plates, horizontally disposed members secured to the side walls of said cabinets for slidably engaging said brackets to support said units, contact members secured to opposite sides of said bus bars, and contact members movably mounted on the rear walls of said cabinets for engaging the contact members on the bus bars.
